ROTARY CASING HEAD.

Application filed March 18, 1926. Serial No. 95,653.

This invention relates to the petroleum industry, and it particularly relates to a novel casing head which is useful in this industry.

5 It is common practice to place an oil string in a well after the well has been drilled, this oil string extending from the oil bearing sands to the surface of the ground. Situated within the oil string near 10 the bottom of the well is an oil well pump, the barrel of which is secured to the lower end of a pump tubing which extends to the surface of the ground through the oil string. The plunger of the pump is connected to 15 the lower end of a string of sucker rods, which string of sucker rods extends upwardly through the pump tubing to the surface of the ground, the upper end thereof being connected to a walking beam whereby the 20 pump plunger is reciprocated in such a manner as to elevate the oil to the surface of the ground. It very often occurs that the well is not straight and may have a considerable curve or crook to it. In such wells 25 the pump tubing is crooked, sometimes to the extent that the string of sucker rods slides against the walls of the pump tubing. The friction on the tubing by the string of sucker rods as it is reciprocated, rapidly 30 wears away the pump tubing and forms a hole therein, which of course causes a leakage and greatly weakens the pump tubing.

It is an object of this invention to provide a casing head in which the pump tubing can 35 be turned any desired distance at any time without making any change in the pumping equipment and without stopping pumping operations, which turning action changes the position of the pump tubing proper and 40 in this manner greatly lengthens the life of the pump tubing since it distributes the wear thereon by the string of sucker rods.

It is another object to provide a casing head in which the pump tubing is constantly 45 rotated at a slow speed during the pumping operation.

Yet another object of our invention is to 50 provide a casing head in which power is diverted from the walking beam that operates the pump plunger to turn the pump tubing in the well when the walking beam is rocking in the operation of the pump.

The casing head of our invention provides a rotatable mandrel to which the pump tubing is connected. This mandrel is surrounded by a stuffing box which prevents leakage of oil therefrom.

It is an object of this invention to provide a casing head in which any leakage of the stuffing box is readily detected.

It is another object of our invention to provide a casing head which is equipped with an elevator assembly, thus eliminating the necessity for any extra connections for starting the tubing from the well.

The elevator of our invention consists of a yoke which is rigidly attached to the casing head and a pair of links which may be detached from the yoke when the elevator is not in use.

It is a further object of this invention to provide a casing head having an elevator lock for locking the elevator links to the yoke, the elevator lock being operable so that the links may be detached from the yoke.

It is a still further object of this invention to provide a casing head having all connections and fittings for pumping a well, thus making it unnecessary to purchase additional surface equipment for the casing head.

It is also an object of this invention to provide a casing head having a novel jack ring used during the pulling and installing of tubing, which jack ring will not be displaced by engagement of any part of the pump tubing unless the part is too large to pass through the jack ring.

It is also an object of this invention to provide a novel and improved pipe slip having features which will be pointed out hereinafter.

Other objects and advantages of the invention will be made evident hereinafter.

Referring to the drawings in which we illustrate our invention,

Fig. 1 is a vertical section through a casing head embodying the features of our invention. This feature shows the parts as assembled during the pumping operation of a well.

Fig. 2 is a fragmentary perspective view of the elevator assembly of the invention.

Fig. 3 is an elevational view of a packing assembly of the casing head of our invention.

Fig. 15 is an enlarged detail of the crown ratchet wheel and pawl mechanism of our invention.

Fig. 16 is a sectional view taken on the line 16—16 of Fig. 15.

Referring to the drawings in detail, 20 represents an oil string, the upper end of which extends from an oil well (not shown).

The oil string has a casing head base 21 secured to the upper end thereof. The casing head base 21 is provided with internal threads at 22 into which the upper end of the oil string 20 is screwed. The casing head base 21 has an opening 23 formed there-through which communicates and is concentric with the interior of the oil string 20. The upper part of the opening 23 is provided in the form of a tapered seat 24 which is provided with an annular and semi-cylindrical depression 25. The upper end of the casing head base 21 is provided with a frusto-conical guide face 27. Threaded openings 28 communicate with the opening 23 directly above the oil string 20 and below the tapered seat 24 into which openings 28 gas pipes 29 are screwed, by means of which gas passing upwardly through the oil string 20 may be conducted from the casing head.

Supported by the casing head base 21 is a casing head body 32. The lower end of the

casing head body 32 is provided in the form of a projection 33 which provides an external tapered seat 34 which extends into the upper end of the opening 23 and engages the internal tapered seat 24 of the casing head base 21. The lower end of the projection 33 is provided with a frusto-conical guide face 35 which may engage the guide face 27 of the base 21, thus guiding the projection 33 properly into the upper end of the opening 23. Directly above the projection 33 the casing head body 32 is provided with an annular ledge 37. A nut 38 is provided for securing the casing head body 32 tightly in place. This nut 38 screws onto external threads 39 formed at the upper end of the casing head base 21 and has an annular shoulder 40 which engages an upper face of the annular ledge 37 in a manner to clamp the casing head body 32 in place.

Formed through the casing head body 32 is an opening 43 through which a mandrel 44 extends. The upper end of the opening 43 is enlarged so as to provide an annular seat 45 on which a thrust bearing 46 may rest. The upper end of the mandrel 44 is also enlarged so as to provide an annular shoulder 47 which engages the upper race of the thrust bearing 46. Therefore, it will be seen that the shoulder 45 of the casing head body 32 supports the thrust bearing, and the thrust bearing by reason of the shoulder 47 supports the mandrel 44. The lower end of the mandrel 44 is provided with threads so that a collar 50 may be secured thereto by means of which the upper end of a pump tubing 51 is secured to the mandrel 44. The lower part of the opening 43 is provided with an enlargement 52 into which the upper part of the collar 50 extends. The mandrel 44 is provided with a passage 54 which connects to the passage of the pump tubing 51.

In the upper part of the opening 43 and surrounding the mandrel 44 is a stuffing box assembly 55 which prevents a leakage of oil or gas through the casing head body around the mandrel 44. The stuffing box assembly 55 consists of lower packing 56 which is placed in the upper part of the opening 43 directly above the thrust bearing 46. Situated above the lower packing 56 is a ring 57. The ring 57 is constructed as shown best in Figs. 1 and 2, being quite narrow at its central part as indicated at 58 to form inner and outer channels and having openings 59 formed therethrough. Formed through the body 32 adjacent to the ring 57 are detecting openings 60. Placed above the ring 57 is intermediate packing 62 above which is placed a lantern 63 which is similar to the construction of the ring 57. The wall of the lantern 63 is narrowed as indicated at 64 and is provided with openings 66. The narrowing of the wall of the

lantern 63 provides inner and outer channels as is illustrated clearly in Figs. 1 and 4. Upper packing 67 is placed above the lantern 63, and engaging the upper part of the upper packing 67 is a follower 68. A nut 69 is advanced on a threaded upper end 70 of the casing head body 32, the nut being for the purpose of depressing the follower 68 so as to compress the lower, central and upper packings. The mandrel 44 is provided with one or more openings 72 in the wall thereof which communicate with the passage 54 thereof and with that part of the stuffing box assembly 55 where the lantern 63 is situated. Formed in the casing head body 32 are openings 73 into which oil pipes 74 are secured. These openings 73 communicate with the portion of the stuffing box assembly where the lantern 63 is placed.

Oil being pumped upwardly through the pump tubing 51 passes into the mandrel 44 and passes therefrom through the opening 72 and the lantern 63 into the oil pipes 74. It is not necessary to provide two oil pipes 74 and one of the openings 73 may therefore be eliminated or be plugged as desired.

Extending through the passage 54 of the mandrel 44 is a polish rod 76 which forms an upper part of a string of sucker rods 77 which extend downwardly through the pump tubing 51 to an oil well pump (not shown) which is situated near the bottom of the well. The upper end of the mandrel 44 is provided with a stuffing box 78. This stuffing box 78 has a lower guide 79 which engages a beveled face 80 formed near the upper end of the mandrel 44. Placed above the guide 79 is a packing 81 which is compressed by means of a follower 82. The follower 82 is urged downwardly by means of a stuffing box nut 83 which is screwed onto threads 85 provided at the upper end of the mandrel 44.

Secured to the mandrel 44 directly below the threads 85 is an elevator yoke 87 of the elevator assembly of the invention. The elevator yoke 87 consists of a hub 88 which surrounds the mandrel 44 and is secured thereto as by welding as indicated at 89. Extending radially outwardly from the hub 88 are arms 90 which have notches 91 formed therein. The elevator assembly also has a pair of links 93 which, when they are in use, attach to the arms 90 of the yoke 87 by extending into the notches 91. The links 93 are adapted to be connected to the elevator hook, as indicated at 94 in Fig. 2. The links 93 may be locked in the notches 91 by means of an elevator lock 96. The elevator lock 96 has an opening 97 through which the mandrel 44 extends. A ring 98 surrounding the mandrel 44 is secured thereto by means of welding as indicated at 99. The lock 96 is supported below the yoke 87 by means of the ring 98. As shown best in

Fig. 2, the lock 96 has arms 100 which may extend under the arms 90 of the yoke 87, as indicated by dotted lines 101, thus locking the links 93 in the notches 91; or may be positioned as shown in full lines in Fig. 2, 70 leaving spaces below the notches 91 and permitting the links to be detached from the yoke 87. The ring 98 is provided with cavities 102 and the lock 96 is provided with pins 103 which are adapted to extend into the 75 cavities 102, thus locking the lock 96 in a certain position. When it is desired to re-position the lock 96, it is moved upwardly into the position indicated by dotted lines 105 in Fig. 1, thus removing the pins 103 80 from the cavities 102. During the installation and removal of the mandrel 44 and the casing head body 32, the links 93 are attached to the yoke 87 as indicated in Fig. 2 and as indicated by dotted lines in Fig. 1. 85 During the operation of the well, however, the links 93 may be removed.

As previously explained, if the well is crooked the pump tubing will be bent and the string of sucker rods will frictionally 90 engage the wall of the tubing and gradually wear it away, and for this reason it is desirable to rotate the pump tubing so that the wear thereon will be distributed around the circumference of the tubing and it will 95 occur if the pump tubing were not rotated.

By use of our invention the pump tubing may be turned as often as desired and at any time without shutting down the pumping equipment. This is done by rotating the mandrel 44. The mandrel 44 may be easily rotated by engaging the upper end thereof by a suitable implement, whereby sufficient leverage to turn the mandrel may be obtained. The mandrel and also the pump tubing may be readily rotated since the mandrel 44 is supported by the thrust bearing 46. The pump tubing may be turned a small fraction of a rotation every few hours, and the wear will therefore be equally distributed around the circumference. This is an attractive feature of the invention since it renders the turning of the pump tubing very simple and does not require the pumping apparatus to be shut down during the turning of the pump tubing.

The feature of providing the elevator assembly is very desirable since it may be economically included as a part of the casing head and there will be no need of having a special elevator for handling the casing head.

Another important feature of our invention resides in the stuffing box assembly 55. 125 If there is a leakage of the stuffing box in an upward direction from the lantern 63 around the upper packing 67, it will be noticed immediately by the presence of oil above the nut 69. If oil leaks from the lan-

tern 63 downwardly around the mandrel 44, it will pass through the ring 57 and egress from the casing head body 32 through the detecting opening 60. On the other hand, 5 in the event that gas should leak upwardly through the opening 43 around the mandrel 44 and the lower packing 56, the gas will egress through the detecting opening 60 and be readily noticed. This construction of 10 stuffing box assembly provides means whereby any leakage of oil or gas may be readily detected and thus readily eliminated.

The parts of our invention just described are those which are employed during the 15 operation of the pump in the well. The casing head of our invention also includes parts which are used during the installing and removing of the pump tubing from the well. During this time the casing head body 20 32, the nut 38, the mandrel 44 and other parts associated directly therewith are removed, only the casing head base 21 remaining. Referring to Fig. 5 in particular, when the pump tubing 51 is being installed in or 25 removed from the well a jack ring consisting of jack ring members 110 are placed in the casing head base 21. The jack ring members 110 have tapered faces 111 which engage the internal tapered seat 24 of the base 30 21. The lower end of the jack ring members 110 are provided with external beveled faces 112 which serve to guide them readily into the opening 23 of the base 21. The upper ends of the jack ring members have 35 radially extending flanges 114. Near the lower ends of the members 110 are provided protuberances 115 which are near the central parts of the members 110 with respect to a horizontal plane as indicated in Fig. 6. 40 These protuberances 115 extend into the depression 25 formed in the seat 24. The protuberances serve as a means for locking the jack ring members 110 in place. The jack ring members 110 are provided with internal 45 tapered faces 116 which cooperate to provide a completely annular seat for the reception of pipe slips 118. As noted clearly in Fig. 6, the jack ring members 110 are slightly less than semi-cylindrical so that spaces 50 119 are provided between the edge faces thereof.

The slips 118 consist of slip members 121 which are divided into sections 122, each section 122 including two slip members 121. 55 As illustrated best in Figs. 7, 8 and 9, each slip member 121 is provided with a vertically extending semi-cylindrical opening 124 which is connected to one vertical edge thereof by means of a slot 125. Each section 122 60 includes a hinged plate 127 for hingeably securing the members 121 of each section 122 together. Each hinge plate 127 consists of enlarged ends 128, which are semi-cylindrical and which rest in the semi-cylindrical opening 124, and a web 129 which attaches 65

the enlargements 128 together and which extends through the slots 125 held in place by pins 126. The slots 125 have non-parallel sides, as clearly illustrated in Fig. 9, and therefore the slip members of each section 70 are adjusted in position, being capable of movement into positions as indicated by dotted lines 130 of Fig. 9. Each section 122 also includes a bail 132. Slots 133 are cut in each member 121, these slots extending 75 downwardly from upper faces 134 thereof. The ends of each bail 132 are enlarged as indicated at 135 and extend into the slot 133 of each slip member 121. The enlarged ends 135 of each bail 132 are pivotally secured 80 in place by a pivot pin 137. Each pivot pin 137 has a shaft portion 138 which extends through one of the slots 133 and through an opening formed in each of the enlargements 135. Each pivot pin 137 is provided with a 85 threaded portion 140 which is screwed into a complementary threaded portion 141 of each slip member 122 for holding each pivot pin in place. Formed at the outer end of each threaded portion 140 is a head 143 by 90 means of which each pivot pin 137 is installed or removed, the head 143 being adapted to engage a face of each slip member 121 whereby it may be frictionally locked from being rotated and removed from place. The 95 construction of the slips is important. The manner of attaching the slip members 121 of each section 122 is important to the invention, and the manner in which the bails 132 are secured to the sections 122 and ac- 100 commodated thereby is also important. As will be noted from Figs. 5 and 7, the bails 132 when not in use may extend in a horizontal plane so that the upper faces 134 of the slip members 121 will be unobstructed. 105

The slip sections 122 are installed in the jack ring which consists of the jack ring members 110, as illustrated in Fig. 5. The slip members 121 have outer tapered faces 143 which are adapted to engage the internal 110 seats 116 of the jack ring members 110. The inner faces of the slip members 121 are serrated as indicated at 145 for the purpose of gripping the pump tubing 51. The slips 118 which are comprised of the sections 122 115 are used for holding the lower part of the pump tubing 51 while a section thereabove is being detached from or secured to this lower end of the tubing. During the time that the tubing is being raised or lowered, 120 the slips 118 are removed from place as shown in Fig. 12. Referring in particular to Fig. 12 the jack ring members 110 are provided with lower internal deflecting faces 148, which are formed at the extreme lower 125 end of the jack ring members.

It is one of the features of this invention, as pointed out in the statement of invention of this application, to provide a jack ring which will not be removed from place due 130

to engagement of the pump tubing therewith. In Fig. 12 we show the pump tubing 51 in engagement with one of the jack ring members 110. It will be seen that this engagement tends to force the jack ring outwardly and retain the protuberance 115 thereof in the annular depression 25. The engagement between the annular depression 25 and the protuberances 115 prevents the 10 jack ring member 110 from being removed by this engagement. In event that the upper end of a collar 149 (Fig. 12) engages the deflecting face 148, this deflecting face 148 will guide the collar so that it will pass through 15 the jack ring. This is the case, however, only when the collar 149 is small enough to pass through the jack ring. If the lower end of the jack ring is engaged by a member which is too large to pass therethrough, 20 the jack ring members 110 will be removed from the casing head base 21. For example, in Fig. 12 dotted lines 151 represent a tubing catcher which is situated near the lower end of the pump tubing 51. This tubing 25 catcher 151 is too large to pass through the jack ring. Therefore, when it engages the lower end thereof it will not pass along the deflecting faces 148, since it is too large, but will engage the lower end of the jack ring 30 members 110 in such a manner as to dislodge them and remove them from the upper end of the opening 23. Since there are spaces 119 between the edges of the jack ring members 110 they may move inwardly so that the 35 protuberances 115 will be removed from the annular depression 25, thus permitting their removal from the casing head base.

As illustrated in Figs. 1 and 2, 13 to 16 inclusive, we have provided a mechanism for 40 rotating the mandrel of our casing head a given amount for each reciprocation of the sucker rod in the pump tubing.

Fig. 13 shows a well 200 in which the oil string 20 is placed. A derrick 202 is erected 45 above the well 200, this derrick being provided with a walking beam pumping mechanism 203. The base 21 of the casing head of our invention is screwed upon the upper end of the oil string 20 at the level of the floor 204 of the derrick 202.

Referring to Fig. 1, it will be seen that a crown ratchet wheel 205, having peripheral crown ratchet teeth 206 and a hub portion 207, is disposed about the mandrel 44 just 50 under the ring 98 and is welded to the ring 98 and mandrel 44 as indicated at 99. An operating lever supporting member 210 is provided with a threaded hole 211 which is screwed upon the threaded upper end 70 of the casing head body 32, as shown in Fig. 1, in advance of the nut 69. A brace member 212 is secured by machine screws 213 to an extending portion 214 of the supporting member 210. Legs 215 of the member 212 project 55 downwardly from the supporting

member 210 to feet 216 which are securely fastened by means of bolts 217 to the floor 204 of the derrick 202. The legs 215 are each bifurcated, a branch arm 218 thereof attaching to the central portion of the supporting member 210. The extended portion 70 214 of the supporting member 210 is provided at one side thereof, as shown in Figs. 15 and 16, with upwardly extending bearing lugs 220 which are apertured to receive a 75 pin 221 upon which is mounted a lever 222. The pin 221 forms the fulcrum for the lever 222. The lever 222, when mounted on the pin 221, is disposed slightly below the crown ratchet wheel 205 and in tangential relation 80 thereto. Extending upwardly from the hub portion 226 of the lever 222 is a bifurcated extension 227 in which a ratchet pawl 228 is pivotally mounted upon a pin 229. The pawl 228 extends toward the point of tangency between the line of the lever 222 and the periphery of the crown wheel 205, lying parallel with the plane of the points of the teeth 206. A lug 230 projects from the hub 226 of the lever 222 so as to be disposed beneath and opposite the pawl 228, as shown in Fig. 15. A spring retaining cavity 231 is formed in the lug 230 and a spring retaining cavity 232 is formed in the lower face of the pawl 228. A helical spring 233 is compressed between the pawl 228 and the lug 230, the opposite ends of this spring being disposed in the cavities 231 and 232. This spring 233 constantly urges the pawl 228 upwardly so that a prong 236, projecting 90 upwardly from the end of said pawl, constantly engages with one of the teeth 206, as shown in Fig. 15. From the hub 226, on the opposite side from the lug 230, extends a lever arm 237 to the end of which a link 100 238 is pivotally secured by a pin 240. The link 238 extends upwardly to where its opposite end is pivotally secured, by a pin 241, to the walking beam 242 of the walking beam mechanism 203. In order to accomplish this pivotal securing of the link 238 to the beam 242 the pin 241 may be projected through any one of a number of holes 244 provided in the beam 242.

In the walking beam mechanism 203 the 115 walking beam 242 is pivotally supported upon a samson post 245 which rests upon the base structure 246. The inner end 247 of the walking beam 242 is secured to the upper end of the polish rod 76 by means of 120 a yoke 248. From the opposite end 250 of the walking beam 242 hangs a pitman rod 252 which is pivotally connected to the crank pin 253 of a crank 254 which is fixed upon the axle 255 of the bull wheel 256. With the 125 rotation of the bull wheel 256 which is driven by a motive power (not shown), the pitman 252 is reciprocated up and down, the walking beam 242 is rocked and the polish rod 76 is reciprocated up and down. This 130

reciprocation of the polish rod 76 causes the sucker rod 77 and the pump plunger attached at the end thereof to reciprocate and results in a pumping of oil upwardly 5 through the oil tubing 51.

The end 247 of the walking beam 242, as shown in full lines in Fig. 13, is in its downward position, while in the position shown in dotted lines in this figure it is in its 10 uppermost position. In reciprocating the polish rod 76 in order to operate the oil pump, the walking beam must continually rock between the dotted and full line positions shown in this figure. This results in 15 the rocking of the lever 222 between dotted and full line positions, as shown in Fig. 13.

In Fig. 15 the lever 222 is shown in the position which it assumes when the end 247 of the rocking beam 242 is in upward position. 20

When the end 247 of the rocking beam 242 moves downwardly the arm 237 of the lever 222 is correspondingly moved downward by the stiff link 240. This causes the pivot 229 25 of the pawl 228 to be rotated in a counter-clockwise direction about the pivot 221 of the lever 222 and causes the prong 236 of the pawl 228 to move in the direction of the arrow 260. Engaging with a tooth 206, during 30 this movement, the prong 236 will move the periphery of the wheel 205 in the direction of the arrow 260 and cause the mandrel 44 to be rotated a given amount. When the lever arm 237 returns from lower position to upper 35 position, the spring 233 is slightly compressed and the prong 236 ratchets freely over the bevel faces of the teeth 206, returning to the position in which it is shown in Fig. 15.

It is obvious that by choice of the hole 244 40 in which to secure the pivot pin 241, the number of teeth 206 traversed by the prong 236 of the pawl 228 upon each of the reciprocations of the end 247 of the walking beam 242 may be determined. Thus, not only are 45 means provided for rotating the pump tubing during the operation of the pump by a walking beam 242, but also the speed of rotation of the pump tubing by the walking beam 242 is made adjustable.

From the foregoing description it will be seen that the casing head of our invention is wholly complete in itself and requires no accessories to be provided other than those 55 which comprise a part of the casing head.

The predominating parts of the invention are enumerated as follows:

The means for rotating the pump tubing is a very important part of the invention, since 60 it permits the tubing to be rotated at will or uniformly during the pumping operation. The packing assembly 55 is important to the invention, since it includes means whereby any leakage of oil or gas may be readily detected so that it may be overcome. The ele-

vator assembly is likewise important to the invention. The feature of having the links 93 detachable is a meritorious feature. The construction of the jack ring is also a salient part of the invention since it prevents 70 the jack ring from being dislodged from the casing head base 21 whenever it is engaged by a collar which is small enough to pass therethrough. It is quite obvious that it would be very inconvenient and take con- 75 siderable time to replace the jack rings every time they have been engaged and dislodged by a collar of the pump tubing. The construction of the jack ring is also important, since it is such that the jack ring will be removed if it is engaged by a part which is too large to pass therethrough. The slips 118 80 also embody features of the invention. The invention in the slips resides in the manner in which the slip members of each section are hingeably attached together and also in the construction which permits the bails 132 to rest in a horizontal position below the upper faces 134 of the members 120 so that they 85 will be unobstructed. 90

We claim as our invention:

1. In combination: an oil string; a pump tubing extending through said oil string; a casing head body supported at the upper end of said oil string; a mandrel rotatably supported by said casing head body and rigidly connected to said pump tubing, said pump tubing being turned when said mandrel is rotated; and a sucker rod string extending through said pump tubing and said 100 mandrel.

2. In combination: an oil string; a pump tubing extending through said oil string; a casing head body supported at the upper end of said oil string; a mandrel rotatably supported by said casing head body and rigidly connected to said pump tubing, said pump tubing being turned when said mandrel is rotated; a stuffing box for preventing a leakage through said casing head body around said mandrel; an oil pipe connected to said casing head body, there being an opening through said mandrel and said stuffing box connecting to said oil pipe; detecting means below said oil pipe for detecting a leakage around said mandrel in a downward direction and a leakage from the upper end of said oil string upward around said mandrel; and a sucker rod string extending through said pump tubing and said mandrel. 110 115 120

3. In combination: an oil string; a pump tubing extending through said oil string; a casing head body supported at the upper end of said oil string; a mandrel rotatably supported by said casing head body and rigidly connected to said pump tubing, said pump tubing being turned when said mandrel is rotated; a yoke attached to said mandrel above said casing head body; a pair of links adapted to engage said yoke; lock 125 130

- means for locking said links in position to engage said yoke; and a sucker rod string extending through said pump tubing and said mandrel.
5. In combination: an oil string; a pump tubing extending through said oil string; a casing head body supported at the upper end of said oil string; a mandrel rotatably supported by said casing head body and rigidly connected to said pump tubing, said pump tubing being turned when said mandrel is rotated; a stuffing box for preventing a leakage through said casing head body around said mandrel; an oil pipe connected to said casing head body, there being an opening through said mandrel and said stuffing box connecting to said oil pipe; detecting means below said oil pipe for detecting a leakage around said mandrel in a downward direction and a leakage from the upper end of said oil string upward around said mandrel; a yoke attached to said mandrel above said casing head body; a pair of links adapted to engage said yoke; lock means for locking said links in position to engage said yoke; and a sucker rod string extending through said pump tubing and said mandrel.
5. In combination: an oil string; a pump tubing extending through said oil string; a casing head base secured to the upper end of said oil string, said casing head base having a tapered internal seat; a casing head body supported by said casing head base, said casing head body having an external tapered seat engaging said tapered internal seat and forming a tight joint; a mandrel rotatably supported by said casing head body and rigidly connected to said pump tubing, said pump tubing being turned when said mandrel is rotated; and a sucker rod string extending through said pump tubing and said mandrel.
6. In combination: an oil string; a pump tubing extending through said oil string; a casing head base secured to the upper end of said oil string, said casing head base having a tapered internal seat; a casing head body supported by said casing head base, said casing head body having an external tapered seat engaging said tapered internal seat and forming a tight joint; a mandrel rotatably supported by said casing head body and rigidly connected to said pump tubing, said pump tubing being turned when said mandrel is rotated; a stuffing box for preventing a leakage through said casing head body around said mandrel; an oil pipe connected to said casing head body, there being an opening through said mandrel and said stuffing box connecting to said oil pipe; detecting means below said oil pipe for detecting a leakage around said mandrel in a downward direction and a leakage from the upper end of said oil string upward around said mandrel.
6. In combination: an oil string; a pump tubing extending through said oil string; a casing head base secured to the upper end of said oil string, said casing head base having a tapered internal seat; a casing head body supported by said casing head base, said casing head body having an external tapered seat engaging said tapered internal seat and forming a tight joint; a mandrel rotatably supported by said casing head body and rigidly connected to said pump tubing, said pump tubing being turned when said mandrel is rotated; a stuffing box for preventing a leakage through said casing head body around said mandrel; an oil pipe connected to said casing head body, there being an opening through said mandrel and said stuffing box connecting to said oil pipe; detecting means below said oil pipe for detecting a leakage around said mandrel in a downward direction and a leakage from the upper end of said oil string upward around said mandrel.

said mandrel; and a sucker rod string extending through said pump tubing and said mandrel.

7. In combination: an oil string; a pump tubing extending through said oil string; a casing head base secured to the upper end of said oil string, said casing head base having a tapered internal seat; a casing head body supported by said casing head base, said casing head body having an external tapered seat engaging said tapered internal seat and forming a tight joint; a mandrel rotatably supported by said casing head body and rigidly connected to said pump tubing, said pump tubing being turned when said mandrel is rotated; a yoke attached to said mandrel above said casing head body; a pair of links adapted to engage said yoke; lock means for locking said links in position to engage said yoke; and a sucker rod string extending through said pump tubing and said mandrel.

8. In combination: an oil string; a pump tubing extending through said oil string; a casing head base secured to the upper end of said oil string, said casing head base having a tapered internal seat; a casing head body supported by said casing head base, said casing head body having an external tapered seat engaging said tapered internal seat and forming a tight joint; a mandrel rotatably supported by said casing head body and rigidly connected to said pump tubing, said pump tubing being turned when said mandrel is rotated; a stuffing box for preventing a leakage through said casing head body around said mandrel; an oil pipe connected to said casing head body, there being an opening through said mandrel and said stuffing box connecting to said oil pipe; detecting means below said oil pipe for detecting a leakage around said mandrel in a downward direction and a leakage from the upper end of said oil string upward around said mandrel; a yoke attached to said mandrel above said casing head body; a pair of links adapted to engage said yoke; lock means for locking said links in position to engage said yoke; and a sucker rod string extending through said pump tubing and said mandrel.

9. In combination: a casing head supported at the upper end of a casing extending into a well, said casing head having a tapered seat, there being a circumferential depression formed in said tapered seat; and jack ring members disposed in said casing head, having tapered faces arranged to engage said tapered seat and having protuberances extending into said depression for preventing said members from being dislodged by engagement of any part which will pass through said jack ring members.

10. In combination: an oil string; a pump tubing extending through said oil string; a casing head body supported at the upper

- end of said oil string; a mandrel rotatably supported by said casing head body and rigidly connected to said pump tubing, said pump tubing being turned when said mandrel is rotated; a sucker rod string extending through said pump tubing and said mandrel; and means for rotating said mandrel.
11. In combination: an oil string; a pump tubing extending through said oil string; a 10 casing head body supported at the upper end of said oil string; a mandrel rotatably supported by said casing head body and rigidly connected to said pump tubing, said pump tubing being turned when said mandrel is rotated; a sucker rod string extending through said pump tubing and said mandrel; a walking beam for reciprocating said sucker rod string; and means, operated by the walking beam while reciprocating said 15 sucker rod string, for rotating said mandrel.
12. An apparatus of the character described, comprising a pump tubing, a means 20 rotatably supporting the pump tubing, a sucker rod string extending through the pump tubing, a working barrel connected with the pump tubing, a plunger in the working barrel connected with the sucker rod string, and a means to operate the sucker rod string.
13. An apparatus of the character described, comprising a pump tubing, a means 25 rotatably supporting the pump tubing, a means to rotate the pump tubing, a sucker rod string extending through the pump tubing, a working barrel connected with the pump tubing, a plunger in the working barrel connected with the sucker rod string, and a means to operate the sucker rod string.
14. An apparatus of the character described, comprising a pump tubing, a means 30 rotatably supporting the pump tubing, a sucker rod string extending through the pump tubing, a working barrel connected with the pump tubing, a plunger in the working barrel connected with the sucker rod string, a means to operate the sucker rod string, and a means operably connected with the last mentioned means to rotate the pump tubing.
15. An apparatus of the character described, comprising a pump tubing, a mandrel connected with the pump tubing, a means 35 rotatably supporting the mandrel, a sucker rod string extending through the pump tubing and mandrel, a working barrel connected with the pump tubing, a plunger in the working barrel connected with the sucker rod string, and a means to operate the sucker rod string.
16. An apparatus of the character described, comprising a pump tubing, a mandrel connected with the pump tubing, a means 40 rotatably and releasably supporting the mandrel, a means to raise and lower the mandrel, a sucker rod string extending through the pump tubing and mandrel, a working barrel connected with the pump tubing, a plunger in the working barrel connected with the sucker rod string, and a means to operate the sucker rod string.

In testimony whereof, we have hereunto set our hands at Los Angeles, California, this 12th day of March, 1926.

BERNARD H. SCOTT.
SAMUEL E. ROSS.
